DRAWER PULL

Steve G. Budai, Cincinnati, Ohio, assignor to The
Globe-Wernicke Co., Norwood, Ohio, a corpora-
tion of Ohio

Application October 20, 1951, Serial No. 17,055

Term of patent 14 years

(Cl. D10—8)

To all whom it may concern:

Be it known that I, Steve G. Budai, a citizen of the United States of America, residing at Cincinnati, in the county of Hamilton and State of Ohio, have invented a new, original, and ornamental Design for a Drawer Pull, of which the following is a specification, reference being had to the accompanying drawing forming a part hereof.

Figure 1 is a plan view of a drawer pull, showing my new design.

Figure 2 is a front elevational view of the same.

Figure 3 is a side elevational view of the same, as seen from the left side of Figure 2.

Figure 4 is an enlarged cross-sectional view taken on the line 4—4 of Figure 2.

I claim:

The ornamental design for a drawer pull, as shown.

STEVE G. BUDAI.
